UNITED STATES PATENT OFFICE.

WILLIAM H. BROWN, OF HASTINGS, NEBRASKA.

COLLAPSIBLE SIGN AND LIGHTING POST.

1,307,655.

Specification of Letters Patent. Patented June 24, 1919.

Application filed April 4, 1919. Serial No. 287,465.

To all whom it may concern:

Be it known that I, WILLIAM H. BROWN, a citizen of the United States, residing at Hastings, in the county of Adams and State 5 of Nebraska, have invented a new and useful Collapsible Sign and Lighting Post, of which the following is a specification.

This invention relates to posts for supporting signs and lighting means for guiding traffic in busy thoroughfares or other places.

The object is to provide a support for signs or lights which is so constructed as to withstand the attacks of heavy winds and 15 the influences of the elements and maintain the signs or light in proper position to be easily seen by drivers of vehicles and to be guided in proper course thereby, and which, in the event of being accidentally collided 20 with by such vehicle, is so constructed as to break or collapse, thus avoiding any material damage to said vehicle or the driver or occupants thereof, and at the same time, capable of being readily and cheaply re- 25 stored to its original condition in the event of such collision.

A further object is to make provision, in such a sign or light support, for easily making the necessary electrical connections for 30 maintaining said light and to render the support easily distinguishable during the day time when the light is extinguished.

A full and complete understanding of the invention may be obtained from a consideration 35 of the following detailed description, taken in connection with the accompanying drawing, it being understood that while the latter shows a practical form of the invention, the latter is not confined to strict con- 40 formity therewith, but may be changed or altered so long as such changes or alterations mark no material departure from the salient features of the invention as specifically pointed out in the appended claims.

45 In the drawing, in which similar reference characters designate corresponding parts throughout the several figures:—

Figure 1 is a side elevation of a collapsible sign and lighting post constructed in 50 accordance with the present invention.

Fig. 2 is a vertical transverse sectional view of the same, the upper portion of the post being in elevation.

In many communities where vehicular 55 traffic is most congested, as at the intersection of streets or roads, the common practice

has been to erect a post of metal, wood or concrete at the center of the two thoroughfares in order to direct the traffic always to the right, and thus avoid a great deal of the 60 confusion otherwise present at such places. This practice has been the means of numerous serious accidents caused by vehicles colliding with such rigidly mounted post or standard and resulting in injuries to the 65 driver or operator of the vehicle and the occupants thereof, to say nothing of the damage caused to said vehicle and the complete demolition of the post or standard.

To avoid such injury to the persons occupying the vehicle which may accidentally collide with such a post and the consequent damage to the vehicle, and to minimize the cost of replacing the post, the present invention has been provided which contemplates 75 the erection at the desired location, of a post constructed of easily breakable parts but constructed and assembled in such a way as to have the appearance of a permanent structure, and to be capable of withstanding all 80 ordinary strains such as might be imposed upon it by the elements or general use.

To this end, the invention comprises a metallic base 1, preferably formed of cast iron and of circular contour, the top platform 2 having integral strengthening ribs 3 formed on the under side thereof in radial relation to a central, threaded bore or aperture 3^a, the outer extremities of the ribs being joined by a circumferential ring 4 cast 90 integrally therewith and adapted to rest upon the ground and support the platform 2 in spaced relation thereto.

Threaded into the aperture 3^a is a short length of pipe 5 comprising a socket secured 95 in its threaded engagement with the base by a lock nut 6, whereby the said pipe is rigidly held in upright position upon the base and at the center thereof. The upper end of the pipe 5 is beveled as indicated at 7 and is 100 adapted to receive therein a section of tube 8 formed of wood, snugly fitting the same and supported at the proper elevation within the pipe 5 by a screw or other projection 9 carried by the wall of the latter.

An upper light-supporting standard 10 formed of metal tubing of the same diameter as the pipe 5, is adapted to rest upon and be supported by the latter, the connection between the two members consisting of a sleeve 110 or coupling 11, having threaded engagement at its upper end with the lower end of the

standard 10 and projecting below the same a sufficient distance to receive the upper end of the pipe 5, the inner diameter of the sleeve or coupling 11 being smooth or free of 5 threads where contacting with the said pipe 5, as indicated at 12 in Fig. 2 of the drawing.

The wooden tube 8 snugly fits the internal diameter of the standard 10 and serves as the main supporting means for the same, the 10 sleeve serving as a shield for the joint between the two tubes to exclude water, etc., therefrom. The beveled upper end of the pipe 5 facilitates the introduction of the sleeve 11 over the same when it becomes 15 necessary to renew the device in case of accident, in a manner to be explained.

The upper end of the standard 10 is adapted to carry any suitable light, an electric lamp globe 12^a being illustrated in the drawing, the bores of the several parts described 20 providing the necessary conduit for the wire connections 13 which may then pass into the conduit 14 connected to the town or city mains.

25 The structure, as far as described, provides a collapsible standard for signaling or warning lights which, by reason of said light is readily visible at night and in order to render the same equally distinguishable 30 by day, it is deemed advisable to form a sheathing or casing for the same which may be painted some light color to attract the eye, and may be further embellished with suitable warning signs, such as "Keep to the 35 right", etc. This sheathing is preferably composed of thin pickets or panels 15 of wood or some other cheap material placed in surrounding relation to the standard 10 and inclined toward each other at the top and 40 slightly spaced apart, thus forming a tapering structure held together adjacent to the top and bottom thereof by wire strands 16, 16, suitably twisted about the same in a well known manner, and maintaining the same 45 spaced relation to each other and to the central upright standard structure.

From the foregoing it will be seen that in 50 the event of the device being accidentally struck by an unruly or misguided vehicle, the sheathing will readily collapse and the standard fall by reason of the breaking of the wooden tube 8 where entering the pipe 5, and the only damage done will be the loss of the globe 12 and lamp therein, the sheathing 55 and the wooden tube as stated, but the danger to the occupants of the vehicle and damage to the latter, is reduced to a minimum, and it will be seen that the parts, to

gether with said sheathing, may be readily replaced at a very slight cost. 60

What is claimed is—

1. A collapsible post for signs, lights, etc., made tubular in form and in sections, and a breakable coupling connecting said sections and including a breakable tube spanning the 65 joint between the sections and maintaining said sections in proper relation to each other, said tube being adapted to break when unusual strain is placed thereon.

2. A collapsible post for signs, lights, etc., 70 made tubular in form and in sections, and a breakable coupling for said sections, said coupling including a collar fast to one section and extending beyond the same and loosely embracing the other section, and an 75 interiorly arranged breakable tube spanning the meeting ends of said sections and extending beyond said ends.

3. A collapsible sign and lighting post comprising a base member, a relatively short 80 upstanding socket member secured centrally to the base member, a tubular standard having lighting means located at its upper end, a collar secured to its lower end and extending below the same and adapted to slip over 85 the upper end of the socket member, a relatively short easily breakable tube fitted within the lower end of the standard and extending into said socket, and a stop carried by the socket and adapted to support said tube, 90 the latter being adapted to readily break upon receiving a blow.

4. A collapsible post for signs, lights, etc., made tubular in form and in sections and a breakable coupling connecting said sections 95 and including a breakable tube spanning the joint between the sections and maintaining said sections in proper relation to each other, said tube being adapted to break when unusual strain is placed thereon, and a sheathing 100 surrounding the said standard in spaced relation thereto comprising a series of spaced slats suitably secured together, extending nearly to the upper end of the standard and resting upon the base, said sheathing 105 being adapted to attract attention and to have indicia imprinted thereon.

In testimony that I claim the foregoing as my own, I have hereto affixed my signature in the presence of witnesses.

WILLIAM H. BROWN.
